HIGH VOLTAGE PROTECTIVE LINK

Elvin A. Thompson, Sharon, Pa., assignor to
Westinghouse Electric Corporation, East Pitts-
burgh, Pa., a corporation of Pennsylvania

Application August 26, 1942, Serial No. 456,210

6 Claims. (CL 200—126)

1

The invention relates generally to electrical apparatus such as transformers, and more particularly, to such apparatus provided with protective devices within the apparatus casing for interrupting the power circuit through the apparatus when subjected to predetermined electrical conditions.

In electrical apparatus, such as polyphase power transformers, it has become customary practice to provide a fusible link or conductor in the high voltage circuit positioned in the insulating fluid of the apparatus for interrupting the connection of the apparatus to the high voltage circuit upon a short circuit of the transformer windings. Such a power transformer assembly is described in Patent 2,198,489, issued to F. L. Snyder on April 23, 1940, and assigned to the same assignee as this application.

In such electrical apparatus, it has been customary to mount the protective link device directly on the lower end of the high voltage bushing below the top level of the insulating liquid or to mount it on a separate support near the lower end of the high voltage bushing. When the fusible conductor of such a protective device is fused to interrupt the circuit, it is necessary to replace the fused conductor, and in order to do this, it has been necessary to lower the level of the insulating liquid within the apparatus casing sufficiently below the level of the protective device as to permit a person to enter the casing through a manhole in the cover of the apparatus and replace the fusible conductor element. It is also frequently necessary to remove the high voltage bushing from its mounting in order to apply the protective link.

It is an object of the invention to provide a protective device for use in apparatus of the character described in which the protective device may be removed and the fusible element renewed without the necessity of lifting the bushing or of draining the oil below its normal level.

It is a further object of the invention to provide a protective device for use in apparatus of the character described in which an operator may remove the fused conductor and replace it with a new one without the necessity for entering the tank or casing of the apparatus.

Other objects and advantages of the invention will be apparent from the following description of a preferred embodiment of the invention, reference being had to the accompanying drawings, in which:

Figure 1 is a vertical sectional view of electrical apparatus to which my invention is applied taken along the line I—I of Fig. 2;

2

Fig. 2 is a top plan view of the apparatus;

Fig. 3 is a vertical sectional view of the protective device that is mounted in the cover of the electrical apparatus;

Fig. 4 is an enlarged sectional view taken along the line IV—IV of Fig. 3; and

Fig. 5 is an enlarged sectional view of a portion of the device shown in Fig. 4.

Referring to the drawings, a tank or casing 10 is provided having a cover 12 and which may include a compartment 13 for containing a main power transformer, a compartment 14 for containing tap changing mechanism, and a compartment 15 for containing metering and control mechanism, as well as other compartments such, for example, as for containing a low voltage circuit breaker between the transformer windings and the low voltage terminals of the apparatus. A lightning arrester 16 is shown mounted above the cover of the apparatus having one terminal 17 grounded on the apparatus casing and the upper terminal 18 connected to a high voltage circuit conductor 19 which is connected also to the terminal stud 21 of a high voltage bushing 22, the lower end 23 of which is connected through terminals 24 and 25 of a protective device 26 to the winding terminals 27 of a main power transformer 28. As shown in Fig. 2, there will be three lightning arresters and three high voltage terminal bushings 22 for a three-phase power transformer, and likewise three low voltage terminal bushings 31 having terminal studs 32 connected to low voltage lightning arresters 33 and also to the low voltage circuit conductors through which power is supplied from the apparatus.

Manhole covers 34 are provided in the cover 12 of the apparatus to permit workmen to enter the apparatus casing for necessary repairs and smaller covers 35 are provided, three in number, directly behind each of the three high voltage bushings 22 for providing access to the protective devices 26 which devices are more clearly shown in Figs. 3, 4 and 5.

The protective device 26 includes a fixed portion 45 permanently mounted within the apparatus and including a base 36 and a barrier or wall 37 of insulating material extending upwardly from the base to a level 38 below the level of the oil within the apparatus. The barrier wall 37 is also provided with openings 39 to permit the flow of the cooling and insulating fluid in and about the parts of the protective device within the barrier wall 37. The terminals 24 and 25 are mounted in the wall or barrier 37 and provided on their inner ends with flat vertically extending contact

members 41 for engaging contact members 42 mounted upon a movable portion of the protective device which includes a cover or plate 43 normally supported below the manhole cover 35 in any suitable manner as by lugs 44, and provided with a handle 45 for raising the plate 43 and the movable portion of the device supported thereby from within the apparatus after removal of the manhole cover 35.

Extending downwardly from the plate 43 are supporting members 46, here shown as four in number, which are attached in any suitable manner to spacer members 47 shown at various levels along the vertical supporting members 46. Two of the vertical spacer members 46, as best shown in Fig. 4, serve as guide members fitting within channels in guide members 48 extending downwardly within the barrier wall 37. Another of the supporting members 46 serves as a support for the contact members 42 which serve as terminals of the removable portion of the device for connecting a fusible conductor 51 between the terminals 24 and 25 of the protective device when the movable portion 40 is in its normal illustrated position. The protective device including the fusible conductor 51 may correspond in principle to that illustrated and described in Patent No. 2,223,726, to J. K. Hodnette, issued December 3, 1940, and assigned to the same assignee as this application. The fusible conductor 51 is shown attached between terminals 52 and 53 by set screws 54 and 55 respectively, the upper terminal 52 being connected to the upper contact member 42 through a terminal head 56, conductor 57, and the lower terminal 53 being connected to the lower contact member 42 by a cable 58.

The fusible conductor element 51 is supported from the upper plate 43 through vertical members 61 which are connected in any suitable manner as by a pin 62 to the terminal head 56. A tube 63 of fiber or other suitable material extends downwardly from the upper terminal 52 about the fusible conductor 51 for aiding in the blowout characteristics of the arc formed when the device operates to interrupt the circuit in a manner now well known. The lower terminal 53 is mounted in a piston 64 normally positioned in a bore within a tubular member 65 of insulating material which may be supported from the terminal head 56 through members 66 and 67.

When the current carried by the apparatus exceeds the safe value sufficiently to cause the fusible conductor 51 to fuse and draw an arc under the insulating liquid in which it is immersed, the gases produced by the arc cause the piston 64 that is attached to the end of the cable 58 to be rapidly ejected from the bore within the tubular member 65 so as to rapidly increase the length of the arc which is extinguished in the insulating liquid surrounding the fusible conductor.

When the fusible conductor 51 has melted and interrupted the circuit, a similar fusible conductor may be replaced by removing the manhole cover 35 and lifting the entire movable portion of the protective device by the handle 45 from within the apparatus casing, causing the contact members 42 to separate from the contact members 41. Thus the entire structure positioned within the vertical supporting members 46 is removed from the apparatus permitting a new fusible wire 51 to be inserted without the necessity of lifting the heavy high voltage bushings or draining the oil to permit a workman to enter the casing of the apparatus.

Modifications in the apparatus illustrated and described may be made within the spirit of my invention, and I do not wish to be limited otherwise than by the scope of the appended claims.

I claim as my invention:

1. In an electrical apparatus including a casing having a liquid insulating medium therein, a cover provided with an opening therein, insulating bushings mounted on and extending through the cover of the casing through which extend leads connecting the apparatus to line circuit conductors, a protective device for the electrical apparatus positioned within the casing and mounted below the opening in the casing cover, said protective device including a base portion and a tubular barrier wall member extending upwardly therefrom and provided with openings therein to permit the flow of the liquid insulating medium within the barrier wall, and guide members extending inwardly from the barrier wall to guide the removable portion against rotation while permitting vertical movement thereof, a pair of fixed contact members mounted on the barrier wall, one connected to the inner end of a circuit conductor supplying energy to the apparatus and one connected to the apparatus, and means for supporting said fixed contact members beneath the normal top level of the liquid dielectric, and a removable portion containing a fusible conductor, said removable portion being insertable and removable through the opening in the apparatus cover and having slideable contact members adapted for engaging the fixed contact members for connecting the fusible conductor between the bushing terminal and the apparatus terminal and positioning the fusible conductor below the top level of the liquid dielectric.

2. In a casing containing an electrical transformer having high-voltage and low-voltage windings, and containing a liquid dielectric within the casing in which the transformer is immersed, and having high-voltage insulating bushings mounted on the cover of the casing through which extend leads connecting said high-voltage windings to high-voltage circuit conductors, a protective device associated with each high-voltage circuit conductor including a conductor which will fuse when subjected to predetermined electrical conditions positioned within the casing and mounted below an opening in the apparatus cover below the top level of the liquid dielectric, said protective device comprising a tubular barrier wall permanently mounted within the apparatus casing beneath the top level of the liquid dielectric and provided with a pair of terminals, one terminal being connected to the inner end of the bushing lead and the other terminal being connected to the high-voltage winding, and a removable portion containing the fusible conductor insertable into the barrier through the opening in the apparatus cover and having terminals therein for engaging the terminals in the barrier wall for connecting the fusible conductor between the high-voltage terminal lead and the high-voltage winding and positioning the fusible conductor below the top level of the liquid dielectric.

3. In a casing containing an electrical apparatus, a liquid dielectric within the casing in which the electrical apparatus is immersed and having insulating bushings mounted on and extending through the cover of the casing through which extend leads connecting the apparatus to line circuit conductors, a protective device for the

electrical apparatus positioned within the casing and mounted below an opening in the apparatus, said protective device comprising a fixed portion permanently mounted within the apparatus casing and a removable portion, the fixed portion comprising a tubular barrier wall of insulating material extending upwardly from a supporting base and having an open upper end terminating below the opening in the apparatus cover at an elevation below the top level of the liquid dielectric, guide members carried by said barrier wall for governing the axial position of the removable portion when inserted into the barrier, and fixed contact members carried by the barrier, the removable portion containing a fusible conductor and having slideable contact members therein for engaging the fixed contact members carried by the barrier for connecting the fusible conductor between the bushing terminal and the apparatus terminal and positioning the fusible conductor below the top level of the liquid dielectric, said removable portion having guide members for cooperating with the guide members on the fixed portion of the device for guiding the contact members into circuit closing positions.

4. In a casing containing an electrical transformer having high-voltage and low-voltage windings, and containing a liquid dielectric within the casing in which the transformer is immersed, and having high-voltage insulating bushings mounted on the cover of said casing through which extend leads connecting said high-voltage windings to high-voltage circuit conductors, a protective device associated with each high-voltage circuit conductor including a conductor which will fuse when subjected to predetermined electrical conditions positioned within the casing and mounted below an opening in the apparatus cover below the top level of the liquid dielectric, said protective device comprising a tubular barrier wall permanently mounted within the apparatus casing beneath the top level of the liquid dielectric and provided with a pair of terminals, one terminal being connected to the inner end of the bushing lead and the other terminal being connected to the high-voltage winding, and a removable portion containing the fusible conductor insertable into the barrier through the opening in the apparatus cover and having terminals therein for engaging the terminals in the barrier wall for connecting the fusible conductor between the high-voltage terminal lead and the high-voltage winding and positioning the fusible conductor below the top level of the liquid dielectric, and guide members associated with said barrier wall and said removable portion for positioning the removable portion axially with respect to the barrier wall to insure engagement of the cooperating terminals carried by said separable portion of said protective device.

5. In an electrical apparatus including a casing having a liquid insulating medium therein, a cover provided with an opening therein, insulating bushings mounted on and extending through the cover of the casing through which extend leads connecting the apparatus to line circuit conductors, a protective device for the electrical apparatus positioned within the casing and mounted below an opening in the apparatus, said

protective device including a fixed portion mounted within the casing and a removable portion cooperatively related thereto, said fixed portion including a base portion and a tubular barrier wall member extending upwardly therefrom and provided with openings therein to permit the flow of the liquid insulating medium within the barrier wall, and guide members extending inwardly from the barrier wall to guide the removable portion against rotation while permitting vertical movement thereof, a pair of fixed contact members mounted on the barrier wall, one of said fixed contact members being connected to the inner end of the bushing lead and the other one of said fixed contact members being connected to the apparatus, and means for supporting said fixed contact members beneath the normal top level of the liquid dielectric, and a removable portion containing a fusible conductor, said removable portion being insertable and removable through the opening in the apparatus cover and having slideable contact members adapted for engaging the fixed contact members for connecting the fusible conductor between the bushing terminal and the apparatus terminal and for positioning the fusible conductor below the top level of the liquid dielectric, the removable portion having a plate member at its upper end and a plurality of pairs of vertical supporting members extending downwardly therefrom, certain of which are positioned to cooperate with the guide members of the fixed portion, and means for supporting the fusible conductor from the plate member between opposite pairs of the vertical supporting members.

6. In a casing containing a liquid dielectric and an electrical transformer immersed in the liquid dielectric and having high-voltage and low-voltage windings, a protective device associated with each high-voltage winding circuit conductor including a conductor which will fuse when subjected to predetermined electrical conditions positioned within the casing and mounted below an opening in the apparatus cover below the top level of the liquid dielectric, said protective device comprising a removable portion and a fixed portion permanently mounted within the apparatus casing beneath the top level of the liquid dielectric and provided with a base portion and a tubular barrier wall member extending upwardly therefrom and provided with openings therein to permit the flow of the liquid insulating medium within the barrier wall, and guide members extending inwardly from the barrier wall to guide the removable portion against rotation while permitting vertical movement thereof, a pair of terminals, one terminal mounted in the barrier wall, one terminal being connected to a circuit conductor and the other terminal being connected to the high-voltage winding, said removable portion being insertable into the casing through the opening in the apparatus cover and having terminals therein for engaging the terminals in the fixed portion for connecting the fusible conductor between the high-voltage terminal lead and the high-voltage winding and positioning the fusible conductor below the top level of the liquid dielectric.
